(57) **CLAIM**

The ornamental design for a case for electronic communications device, as shown and described.

DESCRIPTION

FIG. 1 is a front elevational view of a case for electronic communications device showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front perspective view of the inner shell component of the case shown separately for clarity of disclosure;

FIG. 10 is a rear perspective view of the inner shell component of the case shown separately for clarity of disclosure;

FIG. 11 is a front perspective view of the outer frame component of the case shown separately for clarity of disclosure;

FIG. 12 is a rear perspective view of the outer frame component of the case shown separately for clarity of disclosure;

FIG. 13 is an exploded front perspective view thereof, showing the inner shell and outer frame components separated for clarity of disclosure; and,

FIG. 14 is an exploded rear perspective view thereof, showing the inner shell and outer frame components separated for clarity of disclosure.

Although the case for electronic communications device, in which the claimed design is embodied, consists of an inner shell component and an outer frame component, the claim is
